EYVIND FINSEN, OF ROCHESTER, NEW YORK, ASSIGNOR TO GLEASON WORKS, OF ROCHESTER, NEW YORK, A CORPORATION OF NEW YORK

CHUCK

Application filed June 3, 1929. Serial No. 368,033.

The present invention relates to hydraulic control devices and particularly to hydraulically operated mechanism such as may be used in conjunction with a chucking attachment for releasing the chuck. In a more particular aspect, the invention relates to chucking attachments such as are employed on machines for cutting tapered gears, namely, bevel and hypoid gears.

10 The present invention is an improvement over my prior invention disclosed in application No. 308,537 filed September 26, 1928. Its purpose, in general, is to provide a mechanism more positive in operation, one less liable to get out of order and one which will 15 more readily adapt itself to varying conditions which occur in use.

Other objects of the invention will be apparent hereinafter from the specification 20 and from the recital of the appended claims.

In the drawings:

Figure 1 is a fragmentary plan view of a bevel gear generating machine which is provided with a chucking mechanism incorporating in its construction the features of the present invention, part of the machine and work arbor being shown in section;

Figure 2 is a layout on an enlarged scale of the mechanism of the present invention;

Figure 3 is a fragmentary view of the plunger pump constituting part of this mechanism, parts being shown in section.

The present invention has been illustrated 35 in connection with a chuck for a bevel gear generating machine. The draw-bar of the chuck is constantly urged into chucking position by a coil spring which acts against one end of a piston that is connected to the 40 draw-bar and is housed in a cylinder which is mounted on the work spindle of the machine. The draw-bar is moved to released position against the resistance of the spring by application of fluid pressure to the opposite end of the piston through actuation of a plunger pump which is secured to the frame of the machine at a point convenient to the operator and connected to the cylinder by flexible piping. The pump, piping and cylinder act as a closed hydraulic system, that

is, when the plunger is depressed in the pump, the oil or other liquid used is forced out of the pump into the piping and pressure is applied to the piston to compress the spring and move the draw-bar to released position and when the pressure is released, the spring returns the draw-bar to chucking position forcing the oil out of the cylinder and back through the piping into the pump chamber.

The system is connected by means of a valve-closed duct with a reservoir on the machine. When the plunger of the pump is depressed, the valve is closed. The valve is connected by a stem with the plunger and means is provided for raising the plunger automatically, thus opening the valve as soon as the plunger is raised. The purpose of this construction is two-fold, first, to permit escape of the oil from the system should there be an excess of oil in the system which might prevent the spring from functioning properly to chuck and secondly, to permit oil to be drawn into the system should the supply of oil in the system require replenishing due to leakage.

The present mechanism is constructed so that should any air become entrapped in the system and thereby prevent proper operation of the hydraulic release, it may be pumped out of the pump and out of the system. Means is provided, also, for collecting the oil drawn up by the plunger as it rises to inoperative position and returning the same to the main reservoir of the machine.

With some types of gears, it is impossible with the limited withdrawal movement provided on the work head or tool head of a bevel gear cutting machine to get the work off and on the work spindle conveniently. With the present invention, however, means is provided for drawing the cylinder and with it the draw-bar bodily backward so that after the work has been released, the draw-bar can be drawn out of the bore of the work piece to permit the work piece to drop off of the work spindle while by a reversal of the motion a new blank can be chucked. This improvement very greatly increases the capacity of a gear cutting machine on which it is installed.

Reference may now be had to the accompanying drawings for a more complete understanding of the present invention. The machine shown is of the type described in U. S. Patent No. 1,660,502 issued to James E. Gleason et al. February 28, 1928. It includes a bed or frame 10 on which is slidably mounted a tool head indicated generally at 11 which carries a pair of reciprocating tools, one of which is to be seen at 12 in the drawings. The frame 10 is provided at one end with an upright 13 which is formed with ways 14 which receive the rails 15 of the cradle 16 which is oscillatable on the upright. The upper face 15 of the cradle is provided with arcuate slots 17 and the work head 18 which is angularly adjustable on the upper face of the cradle is held in any adjusted position by means of T-bolts 19 which engage in these slots.

20 Journaled in the work head 18 is a sleeve 20 to which is connected a gear segment 21 which engages a segment 22 that is secured to a relatively fixed part of the machine. The sleeve 20 is connected to the work spindle 24 during cutting by the index mechanism which is enclosed in the housing indicated at 25. The generating motion is imparted to the work spindle by oscillation of the cradle 16 which in turn causes the segment 21 to roll 25 on the segment 22. For a more complete description of this mechanism and its operation, reference may be had to the above mentioned patent. It is to be understood, however, that the present invention is not restricted to use with a machine of the type herein illustrated but is capable of very general application. Reference has been had to a machine on which the present mechanism may be used, simply to make the use, operation and 30 construction of the present invention more readily understandable.

One form of apparatus for clamping the gear blank G to be cut to the work spindle is shown in Figure 1. This includes the draw-bar 30, the horseshoe washer 31 and the arbor 32. The gear blank G and then the horseshoe washer 31 are slipped on to the draw-bar. When the draw-bar is drawn backward in the spindle, the gear is forced 50 against the arbor and the arbor in turn forced into the taper bore of the spindle while the horseshoe washer serves to hold the gear on the draw-bar. The invention is not confined to use with a clamping mechanism such as just described but may be employed in connection with any other suitable clamping mechanism as, for instance, a collet chuck.

The draw-bar 30 is connected at its rear 60 end, as shown in Figure 2 to a piston 35. This piston 35 is housed in a cylinder 36. The cylinder 36 is supported on the spindle 24 by means of the nut 37 which threads into one end of the cylinder and engages the head 65 of a sleeve 38 that is mounted on the draw-

rod 30 and in a suitable recess formed in the end of the work spindle 24.

The draw rod 30 is constantly urged toward and forced into chucking position by a coil spring 40 which surrounds the draw rod 30 and abuts at one end against the head of the sleeve 38 and at the other end against one side of the piston 35. The piston 35 is preferably recessed, as shown, to receive the spring 40 as the compass of the chucking mechanism is thereby reduced to a minimum. To release the work-piece G it is necessary to compress the coil spring 40 and take off the horseshoe washer 31. The spring 40 is compressed by application of fluid pressure to the opposite side of the piston 35, through actuation of a plunger pump 42.

Secured within a hole bored in the end of the cylinder 36, as by means of a pin 43 is a stud 44. This stud is drilled centrally at 45 for a portion of its length and diametrically at 46 to provide a duct for conducting oil or a similar fluid into the cylinder. The stud 44 is threaded at its outer end to receive the nut 48. The nut 48 and the washer 49 which is also mounted on the stud serve to hold the bushing 50 on the stud and through the bushing to hold the sleeve 51 in position on the stud and cylinder. This sleeve 51 is provided with a circular groove 52 that communicates with the duct 46 formed in the stud 44. The sleeve 51 is also drilled to provide a duct 53 that communicates with the groove 52.

A suitable packing is provided, as indicated at 55 to prevent leakage of oil around the stud and sleeve and a leather cup or washer 56 is secured to the piston 35 by the washer 57 and nut 58 to prevent leakage along the piston.

The pump 42 is connected to the sleeve 51 by the coupling 60, the flexible hose 61, and the coupling 62 which includes a manually operable valve 63. The pump 42 is pivotally mounted in a bracket 65 which is secured in any convenient position on the frame of the machine so that the pump will be conveniently located for operation by the operator of the machine. The pump is detachably secured to this bracket by means of a catch 66 which is pivotally secured to the bracket 65 and engages the trunnion pin 67 of the pump.

The pump plunger is shown at 70. It is operated by a hand lever 71 that is pivotally connected to the bracket 65 by the stud 72 and is pivotally connected to the plunger 70 by the pin 73. 74 designates a rod and 75 a weight which is secured to the rod at its outer end. The rod 74 is secured to the lever 71 at a position to normally move the lever 71 and plunger 70 to raised position.

The plunger 70 is hollowed out to receive the stem 76 of the valve 77. This valve 77 is adapted to engage a seat formed in the nipple 78 below the point where the coupling 62 threads into the nipple. The nipple is threaded into the pump chamber 42 proper.

The valve 77 controls the duct 79 which may be connected with the oil reservoir or one of the oil pumps of the machine or may communicate by means of a tube 81 with a reservoir such as shown at 80 in Figure 2 which is threaded onto the end of the nipple 78.

The valve stem 76 is threaded at its upper end to receive the nut 82 and the lock-nut 83.

The system comprising the pump 42, nipple 78, coupling 62, hose 61, coupling 60, duct 53, groove 52, ducts 46 and 45 and the cylinder 36 is adapted to be kept as full of oil as is possible when the draw-bar is in clamping position and the piston 35 is in its rearward position in the cylinder 36 under actuation of the spring 40 and when the plunger 70 is in raised position. When the plunger 70 is depressed by operating the lever 71, the column of oil in the pump 42 first closes the valve 77 and is then forced through the piping 61 into the cylinder 36 to compress the spring 40, move the draw-bar 30 forward in the work spindle 24 and release the work-piece. As soon as the operator releases the lever 71, as after removing the completed gear and chucking a new blank, the spring forces the piston 35 rearwardly again to move the draw-bar 30 again to chucking position. This operation is accelerated by the action of the weight 75 which lifts the lever arm 71 and the plunger 70 automatically, thus affording room in the pump 42 for the column of oil which is forced out of the cylinder 36 by the return of the piston 35 to chucking position. As the plunger 70 rises, the bushing 84 which is threaded into the lower end of the plunger engages the nut 82 lifting the valve 76 and opening the system through the duct 79. The nut 82 is adjusted so that the bushing 84 will engage it and open the valve 77 just before the rod 74 strikes the stop ledge 86 on the bracket 65.

It is impossible with present manufacturing methods to eliminate entirely variation in gear blank dimensions. Some blanks will always be slightly larger than others. If the system were to remain closed at all times, thus containing a constant volume of oil, the chucking attachment would not be flexible enough to take care of the variation in gear sizes which normally occur in practise. The chucking attachment might be adjusted to take a gear of a particular size. If a gear a few thousandths of an inch smaller than this size occurred in the lot, to chuck it properly, the draw-rod 30 and piston 35 would have to be forced back farther than for the standard sized gear. But if the volume of oil in the system were constant, this would resist the movement of the piston 35 back farther than the predetermined distance so that the gear would not be properly seated on the arbor and the arbor in the spindle. With the system opened, however, automatically when the lever 71 is released, should a

small gear occur in the lot, the chucking attachment will function just as well as for a gear of the standard size for the extra volume of oil will be forced out of the system through the duct 79.

When a gear a few thousandths oversize occurs, a greater volume of oil is required in the system to release the chuck. Oil leakage is bound to occur and if the mechanism is to work properly at all times, this must be replenished. A further advantage of opening the valve 77 automatically when the lever 71 is released is that if for any reason the volume of oil in the system falls below the amount required to operate the release, the system will be automatically replenished by drawing oil into the system on the upstroke of the valve 77 and plunger 70. Thus, at all times, the mechanism operates automatically to maintain its maximum efficiency.

If the reservoir 80 is used, it can be refilled from time to time through the oil-cup 88 and the volume of oil in the reservoir can be observed at any time through the sight-glass 89.

With a mechanism functioning as described, it is necessary to exclude air entirely from the system. If there were any air in the system it would simply compress on the down stroke of the plunger 70 and the chuck would not be released. Through a very simple and ingenious arrangement, any air which might become entrapped in the pump can be readily pumped therefrom, and a plug or valve is provided at some other convenient point in the system to permit forcing air out of the rest of the system.

The plunger 70 of the pump is drilled at its upper end, above the chamber for the valve stem 76, to provide a duct 90 (Fig. 3) which is normally closed by the ball-valve 91 which is held clamped in its seat by the set-screw 92 that threads into the side of the plunger. To empty the pump of air, the handle valve 63 is closed and the set screw 92 is turned to release the ball 91 from its seat. Then the plunger 70 is moved down in the pump chamber by operating the lever 71. With the lever held down the set-screw 92 is retightened. Then the plunger is raised and the operations repeated until oil begins to seep around the set-screw 92, thus signifying that the pump chamber is empty of air. The set-screw 92 is then threaded up to force the valve 91 back into its seat.

To exclude air from the rest of the system, the cylinder 36 is turned till the plug 94 (Fig. 2) which is threaded into the cylinder is on the upper side of the cylinder. The plug 94 is then unthreaded a turn or two. The spring 40 is then compressed as far as possible by actuating the pump and while the pump lever is held down, the hand valve 63 is closed. The lever 71 is then released sucking more oil into the pump. The hand

valve is then opened and the additional oil in the pump forced into the system. This procedure is continued until oil begins to seep around the threads of the plug 94. When the oil seeps out along the plug, the system will be free of air and the plug again tightened.

With each stroke of the plunger 70 upward, some of the oil in the pump will follow the plunger. To avoid the nuisance and inconvenience of this oil leaking over the machine or onto the floor, I have provided means whereby the oil is wiped off of the plunger on each down stroke and returned to the sump or reservoir in the machine. The cap 95 of the pump is recessed as shown at 96. Thus as the plunger 70 is moved downwardly, the oil is wiped off of the plunger into this pocket or recess 96. It flows thence into a duct 97 drilled into the cap 95 and into a tube 98 inserted in this duct 97. The tube 98 extends beyond the side of the pump and over a pocket 99 formed in the bracket 65. The oil dripping from the tube 98 falls into this pocket 99 and is conducted through the duct 100 into the sump of the machine. The tube 98 is always over the pocket 99 regardless of the pivotal movement of the pump.

The cylinder 36 can be adjusted on the nut 37 to permit of taking care of a wide range of gears. In the machine shown, the tool head 11 is moved backward to permit of taking off a finished gear or chucking a new blank. In other types of machines, the work head is moved away from the tools for this same purpose. Where flat gears are being cut, for instance, it frequently occurs that the withdrawal movement provided on the tool head or work head of the machine is not sufficient to carry the work away from the tools far enough to permit chucking or unchucking a gear. The present improvement incorporates as one of its features an arrangement whereby, once the gear has been released, the draw-rod 30 can be drawn inwardly to clear the bore of the gear and permit the gear to drop off the spindle. This is illustrated in Figure 1.

Secured to the sleeve 51 at a point approximately 90° away from the point at which the coupling 60 is threaded into the sleeve is a rod 102 which is also supported from the work head by the arms 103 and 104 in which the rod is slidable. Secured to the rod as by a set-screw (not shown) is a collar 105 to which is pivoted a link 106 which is pivoted to a bell-crank lever 107, the long arm of which is formed with an operative handle 108. The bell-crank lever 107 is pivoted on a T-bolt 110 which is adjustable with the work head in the slot 17 of the face of the cradle.

It will be seen that through the slidable connection between the stud 38 (Fig. 2) and the work spindle 24, that when the lever arm

108 is turned to the left from the position shown in Figure 1, the rod 102 will be moved rearwardly to draw the cylinder 36 and through the spring connection between the cylinder and the piston 35 to draw the bar 30 rearwardly in the spindle 24. A collar 111 can be adjusted along the rod 102 and held by a set-screw to limit the movement of the rod 102 as desired.

The rod 102 holds the sleeve 51 against movement during the roll of the work spindle so that the flexible hose 61 is not twisted back and forth. To further protect the hose against wear, bell-shaped guards 114 and 115 (Fig. 2) are provided where the hose connects, respectively, to the sleeve 51 and the coupling 62. A sleeve 116 which is belled at both ends is secured to the frame of the machine to support the hose at an intermediate point.

To take a gear off of the chuck, the operator grasps the lever 71 to depress the plunger 70, thus forcing oil into the cylinder 36 and compressing the spring 40 and moving the draw-bar 30 forward in the spindle. The operator can then take the horseshoe washer 31 off of the draw-bar. If the tools and blank have been separated far enough by the movement of the tool head, the completed gear can then be slipped off of the draw-bar and a new blank positioned thereon. If the range of movement of the tool head is not sufficient to enable the gear to be taken off and clear the tool, the operator swings the lever 107 to withdraw the draw-bar into the spindle and let the gear drop off.

In chucking a new blank, the spring 40 is held compressed, the operator positions the blank on the draw-bar, which will have been returned to position by movement of the handle 108 if it had been previously withdrawn, and the horseshoe washer 31 is slipped onto the draw-bar. The lever 71 is then released and the spring 40 functions automatically to clamp the gear blank to the spindle.

While the invention has been described in connection with a particular embodiment and in connection with a particular use for that embodiment, it will be understood that it is capable of further modification and use and that this application is intended to cover any variations, uses, or adaptations of the invention, following, in general, the principles of the invention and including such departures from the present disclosure as come within known or customary practise in the art to which it pertains and as may be applied to the essential features hereinbefore set forth and as fall within the scope of the invention or the limits of the appended claims.

Having thus described my invention, what I claim is:

1. The combination with a cylinder, a piston movable therein and means for moving said piston in one direction in said cyl-

- inder, of a pump and piping connecting the pump with the opposite end of the piston, said pump, piping and cylinder forming a closed hydraulic system such that when the pump is actuated, a column of liquid is forced from the pump chamber into the cylinder to move the piston in the direction opposite to that first mentioned, and when the pump is released, the first named means moves the piston in the first named direction in the cylinder forcing the liquid from said cylinder back into the pump chamber, and means for automatically connecting said system during the last named movement with a source of liquid supply to allow liquid to flow in either direction between the system and the source of supply depending on the amount of liquid in the system. 5 70
2. The combination with a cylinder, a piston movable therein and spring means for constantly urging the piston in one direction in the cylinder, of a pump and piping connecting the pump with the opposite end of the piston, said pump, piping and cylinder forming a closed hydraulic system such that when the pump is actuated, a column of liquid is forced from the pump chamber into the cylinder to move the piston in the direction opposite to that first mentioned, and when the pump is released, the spring means moves the piston in the first named direction in the cylinder forcing the liquid from the cylinder back into the pump chamber, and means for automatically connecting said system during the last named movement with a source of liquid supply to allow liquid to flow in either direction between the system and the source of supply depending upon the amount of liquid in the system. 10 75
3. The combination with a cylinder, a piston movable therein, and means constantly urging the piston in one direction in the cylinder, of a plunger pump, piping connecting the pump with the cylinder at the opposite end of the piston, a reservoir connected with the pump, a valve governing said connection adapted to be closed when the plunger is depressed in the pump to form a closed hydraulic system between the pump and cylinder such that in the further depression of the pump hydraulic pressure is applied to the piston to move it against resistance of the first named means, means for automatically raising the plunger in the pump when released, and means for automatically opening said valve on said last named movement. 15 80
4. The combination with a cylinder, a piston movable therein, and means constantly urging the piston in one direction in the cylinder, of a plunger pump, piping connecting the pump with the cylinder at the opposite end of the piston, a reservoir connected with the pump, a valve controlling said connection adapted to be closed when the plunger is depressed in the pump to form a closed 20 85
- hydraulic system between the pump and cylinder such that on further depression of the plunger a hydraulic pressure is applied to the piston to move it against the resistance of said first named means, said valve having a stem slideable in said plunger, interengaging means on the plunger and stem for opening said valve when the plunger is raised, and means for automatically raising said plunger when released. 25 90
5. The combination with a cylinder, a piston reciprocable in said cylinder and means constantly urging said piston in one direction in said cylinder, of a plunger pump, piping connecting the pump with the cylinder at the opposite end of the piston, a bracket on which the pump is pivotally mounted, a lever for operating the plunger pivoted on said bracket and pivotally connected to the plunger, means for urging said lever constantly in one direction to move the plunger to raised position, a reservoir connected with the pump, a valve controlling said connection adapted to be closed on depression of the plunger to form a closed system between the pump and cylinder whereby on further depression of the plunger hydraulic pressure is applied to the piston to move it against the resistance of the first named means, said valve having a stem slideable in said plunger, and means for connecting the valve to the plunger so that when the plunger is raised, the valve is opened. 30 95
6. The combination with a spindle, a draw rod reciprocable in said spindle, a cylinder, a piston movable in the cylinder, and means for moving the piston in the cylinder in opposite directions to move the draw rod to and from chucking position, of means for moving the cylinder and with it the piston and draw rod bodily relative to the spindle. 35 100
7. In a tapered gear cutting machine, a tool, a support, a work head angularly adjustable on the support to bring the root surface of the blank into tangency with the cutting plane of the tool, a work spindle journaled in the head, a draw-rod for clamping the work to the work spindle, a cylinder mounted on the head, a piston movable in the cylinder and connected to the draw rod, means for moving the piston in opposite directions in the cylinder for operating the draw rod, and means mounted on the support and adjustable angularly thereon with said head for moving the cylinder bodily relative to the spindle. 40 105
8. In a tapered gear cutting machine, a tool, a support formed with an arcuate T-slot on its upper face, a work head adjustable angularly on said support to bring the root surface of the blank into tangency with the cutting plane of the tool, means adapted to engage in said slot to secure the work head in any adjusted position, a work spindle journaled in the head, a draw rod for clamping 45 110
- 50 115
- 55 120
- 60 125
- 65 130

the work to the work spindle, a cylinder mounted on the head, a piston movable in the cylinder and connected to the draw rod, means for moving the piston in opposite directions in the cylinder for operating the draw-rod, a bolt secured in the slot of the support and adjustable therein, a rod connected to the cylinder, and a bell-crank lever pivotally mounted on the bolt for actuating said rod to move the cylinder bodily relative to the spindle.

9. In a tapered gear cutting machine, a tool, a support, a work head angularly adjustable on the support to bring the root surface of the blank into tangency with the cutting plane of the tool, a work spindle journaled in the head, a draw rod for clamping the work to the work spindle, a cylinder mounted on the head, a piston movable in the cylinder and connected to the draw rod, a spring housed in the cylinder for urging the draw rod constantly to clamping position, means for moving the piston in the opposite direction, and means mounted on the support and adjustable angularly thereon with the head for moving the cylinder bodily relative to the spindle.

10. The combination with a cylinder, a piston movable therein and means constantly urging the piston in one direction in the cylinder, of a plunger pump, piping adapted to connect the piston to the pump, a manually operable valve for shutting off said connection, a reservoir connected to the pump, a second valve controlling said connection adapted to be closed on depression of the plunger in the pump and automatically opened when the plunger is raised, and a third valve housed in the plunger at a point external of the pump, and means for keeping said third valve closed during the normal operation of the pump, said means being releasable to permit opening of the third valve so that when the hand operated valve is closed, the plunger may be operated to pump air out of the pump chamber.

11. The combination with a cylinder, a piston movable therein and means constantly urging the piston in one direction in the cylinder, of means for applying fluid pressure to the opposite end of the piston for forcing the piston in the opposite direction comprising a plunger pump, and piping adapted to connect the piston to the pump, and a manually operable valve, a reservoir connected to the pump, a second valve controlling said connection adapted to be closed on depression of the plunger in the pump and automatically opened when the plunger is raised, a ball-valve housed in the plunger, a screw for keeping said ball valve closed during the normal operation of the pump and adapted to be released when the hand valve is closed to permit the plunger to be operated to force the air out of the pump chamber.

12. In combination with a machine having an oil reservoir therein, a bracket secured to the machine, a plunger pump pivotally mounted thereon, a lever arm pivotally connected to the bracket and pivotally connected to the plunger of the pump to operate said plunger, means external of the pump chamber for wiping oil from the plunger, a duct extending beyond the periphery of the pump chamber for conducting the wiped oil to one side of the chamber, and a duct in said bracket beneath the first named duct for catching the oil dripping from the first duct and returning the same to the reservoir in the machine.

13. The combination with a spindle, of a chucking attachment therefor comprising a draw rod reciprocable in the spindle, a cylinder mounted on the spindle, a piston secured to the draw rod and reciprocable in the cylinder, means for moving the piston in one direction of the cylinder, a plunger pump, piping connecting the pump to the cylinder at the opposite end of the piston, said cylinder, piping and pump constituting, in operation, a closed hydraulic system whereby when the plunger is depressed in the pump the piston is moved in the cylinder, a valve communicating with the system adapted to be closed on depression of the pump plunger and means connecting the valve with the plunger for positively opening the valve when the plunger is raised in the pump.

14. The combination with a spindle, of a chucking attachment therefor comprising a draw rod reciprocable in the spindle, a cylinder mounted on the spindle, a piston secured to the draw rod and reciprocable in the cylinder, means constantly urging the piston in one direction in the cylinder, a plunger pump, piping connecting the pump to the cylinder at the opposite end of the piston, said cylinder, piping and pump constituting, in operation, a closed hydraulic system whereby when the plunger is depressed in the pump the piston is moved in the cylinder, a valve communicating with the system adapted to be closed on depression of the pump plunger and means connecting the valve with the plunger for positively opening the valve when the plunger is raised in the pump.

15. The combination with a spindle, of a chucking attachment therefor comprising a draw rod reciprocable in the spindle, a cylinder mounted on the spindle, a piston secured to the draw rod and reciprocable in the cylinder, means constantly urging the piston in one direction in the cylinder, a plunger pump, piping connecting the pump with the cylinder at one end of the piston, said cylinder, piping and pump constituting in operation a closed hydraulic system whereby when the plunger is depressed in the pump the piston is moved in the cylinder against the resistance of the first named means, a valve com-

5 municating with the system adapted to be closed on depression of the pump, means connecting the valve with the plunger for opening the valve when the plunger is raised in the pump, and means for positively raising the plunger when released.

16. The combination with a spindle, of a chucking attachment therefor comprising a draw rod reciprocable in the spindle, a cylinder mounted on the spindle, a piston secured to the draw rod and reciprocable in the cylinder, means constantly urging the piston in one direction in the cylinder, a plunger pump, piping connecting the pump 10 to the cylinder at the opposite end of the piston, said cylinder, piping and pump constituting, in operation, a closed hydraulic system whereby when the plunger is depressed in the pump the piston is moved in the cylinder against the resistance of the first named 15 means, a reservoir connected with the pump, a valve controlling said connection adapted to be closed on depression of the plunger, means connecting the valve with the plunger 20 for opening the valve when the plunger is raised in the pump, and means for positively raising the plunger when released.

17. In a machine for cutting tapered gears, a tool, a work head adjustable angularly to 25 move the root surface of the blank into tangency with the cutting plane of the tool, a work spindle journaled in the work head, chucking mechanism therefor comprising a draw rod reciprocable in the spindle, a cylinder mounted on the spindle, a piston secured 30 to the draw rod and reciprocable in the cylinder, means for moving the piston in one direction in the cylinder, a plunger pump, piping connecting the pump to the cylinder 35 at the opposite end of the piston, said cylinder, piping and pump constituting, in operation, a closed hydraulic system whereby when the plunger is depressed in the pump the piston is moved in the cylinder, a valve 40 at the opposite end of the piston, said cylinder, piping and pump constituting, in operation, a closed hydraulic system whereby when the plunger is depressed in the pump the piston is moved in the cylinder, a valve 45 communicating with the system adapted to be closed on depression of the plunger and means connecting the valve with the plunger for positively opening the valve when the plunger is raised in the pump and means for 50 moving the cylinder bodily relative to the spindle.

18. The combination with a cylinder, a piston movable therein, spring means operative on one end of said piston to constantly 55 urge the same in one direction, a plunger-pump, piping connecting the pump to the cylinder at the opposite end of the piston, said pump, piping and cylinder comprising a substantially closed hydraulic system containing a substantially constant volume of liquid whereby when the plunger is depressed in the pump chamber, the liquid is forced into the cylinder to move the piston against the resistance of the spring and when 60 the plunger is moved outwardly of the pump 65

chamber, the spring forces the piston in the first named direction forcing the liquid from the cylinder back into the pump chamber, said cylinder having a port therein communicating with a source of liquid supply external to the system, a valve adapted to be seated by depression of the pump plunger to close said port and by outward movement of the pump plunger to open said port, and means constantly urging said plunger outwardly.
